UNITED STATES PATENT OFFICE.

BERTRAM A. STROOCK, OF NEWBURGH, NEW YORK, ASSIGNOR TO STROOCK PLUSH COMPANY, OF NEWBURGH, NEW YORK, A CORPORATION OF NEW YORK.

DESIGN FOR PLUSH FABRIC.

47,277.

Specification for Design. Patented Apr. 27, 1915.

Application filed February 8, 1915. Serial No. 6,880. Term of patent 3½ years.

To all whom it may concern:

Be it known that I, BERTRAM A. STROOCK, a citizen of the United States of America, residing at Newburgh, in the county of Orange and State of New York, have invented a new, original, and ornamental Design for Plush Fabric, of which the following is a specification, reference being had to the accompanying drawing.

In the drawing the figure is a plan view of a plush fabric illustrating my new design.

I claim:

The ornamental design for plush fabric, as shown.

BERTRAM A. STROOCK.
